HEAT EXCHANGER SUPPORT

Ray T. Jenkins, Houston, Tex.

Application November 26, 1954, Serial No. 33,249

Term of patent 14 years

(Cl. D81—21)

Fig. 1

Fig. 2

Fig. 1 is a view in side elevation of a heat exchanger support embodying my new design; and

Fig. 2 is a view in end elevation thereof.

The opposite side and end are like the respective side and end shown.

The top not shown has rows of heat exchanger fins running longitudinally thereof in spaced relation. The design is characterized by the sides, ends and supporting members having the configurations and appearances shown.

I claim:

The ornamental design for a heat exchanger support, substantially as shown and described.
